United States Patent Office

Des. 228,369
Patented Sept. 11, 1973

228,369

WRITING IMPLEMENT

Roland Longarzo, Valley Stream, N.Y., assignor to Consolidated Foods Corporation, Chicago, Ill.

Filed Oct. 5, 1971, Ser. No. 186,596

Term of patent 14 years

Int. Cl. D19—06

U.S. Cl. D74—17 B

FIG. 5

FIG. 2

FIG. 1

FIG. 3

FIG. 4

FIG. 6

FIG. 1 is a front elevation of a writing implement showing my new design;

FIG. 2 is a side elevation;

FIG. 3 is a side elevation opposite to that shown in FIG. 2;

FIG. 4 is a rear elevation;

FIG. 5 is a top plan view; and

FIG. 6 is a bottom plan view.

I claim:

The ornamental design for a writing implement, substantially as shown.
